UNITED STATES PATENT OFFICE.

JOHN H. DYNES, OF CLEVELAND, OHIO.

ADVERTISING DEVICE.

SPECIFICATION forming part of Letters Patent No. 755,221, dated March 22, 1904.

Application filed January 25, 1904. Serial No. 190,427. (No model.)

To all whom it may concern:

Be it known that I, JOHN H. DYNES, a citizen of the United States, and a resident of Cleveland, county of Cuyahoga, State of Ohio, have invented certain new and useful Improvements in Advertising Devices, of which I hereby declare the following to be a full, clear, and exact description, such as will enable others skilled in the art to which it appertains to make and use the same.

The invention has especial reference to novel packages for the general distribution of samples or of attractive advertisements; and the objects are to provide an inclosure having automatically-opening walls which when released separate instantly to disclose an object, such as a figure, trade-mark, or other characteristic device. The entire package is designed to be of such a form as to attract attention to itself and to the goods designed to be advertised thereby.

My invention further consists in the combination and arrangement of parts and construction of details, as hereinafter described, shown in the accompanying drawings, and specifically pointed out in the claims.

In the accompanying drawings, Figure 1 is a perspective view of the advertising-package closed; and Fig. 2 is a plan view of the inner face thereof before the package has been closed, showing a figure standing upright in the center upon the bottom portion. Fig. 3 shows a slot in one of the overlapping side leaves. Fig. 4 shows modified means for fastening the leaves.

The exterior of the package can be covered with directions for operating the device and ornamental matter, and the interior should contain the advertisement printed on the inner faces of the leaves.

In the figures, 1 is the bottom of the package, and 2 represents a plural number of sides whose edges 3 are shaped to form an inclosure when brought together. These may be curved, as shown, or angular, the only requirement being that they should form an inclosure when brought together. At the top of each side or leaf is seen the overlapping portion 4, through a perforation 9 in which passes the cord 5,

which is secured to the middle of the bottom 5c at 6.

In order to close the package after the sample has been inclosed, the sides are brought together and the cord is tightened in a straight line through the package. A knot 7 is then tied in the cord just above the last overlapping leaf, and the package will remain closed until the cord is cut with a knife or scissors just below the knot, when the sides will fly apart and disclose the contents. To facilitate the spring action of the sides, they may be made of more or less resilient material, such as bristol-board or celluloid, and further resilience can be obtained by means of strips of rubber, whalebone, or other elastic material secured to the sides and bottom, if desired, as shown in partially-dotted lines in Fig. 2 at 8.

The particular attractiveness of this device is found in the mode of its use. The device when closed is suspended in a conspicuous place, such as on the front door of a house, on a fence-post, or telegraph-pole, and natural curiosity will insure cutting the cord to see it open and disclose its contents. It can be hung over a knob or nail or fastened by a pin 75 through the loop 13.

The sample of the advertised goods may be held in the hand of the figure or supported otherwise by the contained object, as a vase or urn, or may be simply placed within the receptacle. There should be no advertising matter on the outside of the package.

As shown in Fig. 3, diagonal slots 10 can be used to insert the cord in the overlapping ends of the side leaves, since it can be done more easily than by threading the cord through small perforations. Again, in Fig. 4 a portion of the overlapping ends are provided with square holes 11, and the others with tongues 12, by means of which the parts are detachably joined together, a supporting-string being preferably employed.

Having described my invention, what I claim as new, and desire to secure by Letters Patent, is—

1. In an advertising device, a plurality of side pieces and integral bottom, so arranged as to form a closed package when the adjacent

edges of the sides are brought together, in combination with perforated overlapping upper extremities for the side portions, a cord secured to the bottom and passing through the 5 perforations in the overlapping sides, and means for retaining the sides in their closed position, substantially as described.

2. In an advertising device, in combination with side pieces shaped to form a closed pack-
10 age when their meeting edges are brought together, and an integral bottom, of a cord se-
cured to said bottom, overlapping upper ex-
tremities to the sides through which the cord
passes, a knot on the cord above said over-
lapping extremities, and an image or charac-
15

teristic device within the package, substan-
tially as described.

3. In combination in a sample-package, a
bottom, integral side leaves, adapted to form
an inclosure for advertising matter when 20
brought together at their apices, means for
detachably securing said leaves together, and
means for forcibly separating said side leaves
when released, substantially as described.

In testimony whereof I hereunto set my 25
hand this 21st day of January, 1904.

JOHN H. DYNES.
